UNITED STATES PATENT OFFICE

DAVID W. NORRIS, OF PASADENA, CALIFORNIA

DESIGN FOR A FURNACE

Application filed February 4, 1932. Serial No. 42,739. Term of patent 14 years.

To all whom it may concern:

Be it known that I, DAVID W. NORRIS, a citizen of the United States, and a resident of Pasadena, in the county of Los Angeles and State of California, have invented a new, original, and ornamental Design for a Furnace, of which the following is a specification, reference being had to the accompanying drawing, forming part thereof.

Figure 1 is a top plan view of a furnace embodying my new design.

Figure 2 is a front elevation of the furnace; and

Figure 3 is a side elevation of the same.

I claim:

The ornamental design for a furnace substantially as shown.

Des Moines, Iowa, January 27, 1932.

DAVID W. NORRIS,
